METHOD OF MAKING A RESILIENT METAL-
LIC BUNCHSylvester W. Grater, Philadelphia, Pa., assignor
to John W. Gottschalk Mfg. Company, Phila-
delphia, Pa., a corporation of Pennsylvania

Application November 4, 1938, Serial No. 238,754

4 Claims. (Cl. 140—71)

The object of this invention is to devise a novel method of making a flexible and resilient metallic bunch from a coreless helical strand which has had imparted to it an inherent tendency to curl. The strand is formed from a metallic strand which may be oxidizable or non-oxidizable, and if a round wire is used, it is preferably deformed in cross section by a deforming operation, to change its contour and increase the number of abrading edges of the strand. The strand is subjected to a curling operation by known methods, preferably by drawing the strand under tension over a curling edge to impart to it an inherent tendency to form a helical coil, or by wrapping it around a mandrel with a flier. The strand thus formed is tensioned and coreless and has adjacent coils preferably disposed in close proximity to each other.

In carrying out my novel method, a strand of the character herein disclosed with the tension relaxed and in an unstretched condition is wound on a reel, core, spool, spindle, or mandrel, each of which can be considered as a mechanical equivalent of the others, until sufficient amount of mass for the desired size of bunch has accumulated. The mass after the winding operation is completed and in a loose condition is stretched into an elongated skein form and released to allow it to retract, thus causing an interlocking of coils of adjacent turns.

The stretching and retracting operations may be repeated a desired number of times and the mass when released may then, if desired be worked together mechanically or manually so that coils of adjacent turns are more thoroughly interlocked throughout the major portion of the bunch.

With the foregoing in view, a further object of the invention is to wind a tensioned, helical, coreless strand in an unstretched condition, and, after winding, stretching and retracting the turns either mechanically or manually, to cause the interlocking of coils of adjacent turns.

Other novel steps and features of the method will hereinafter clearly appear in the detailed description and the appended claims.

In the accompanying drawings I have shown one of several constructions which can be advantageously employed in carrying out in practice my novel method.

Figure 1 is a side elevation of a machine for curling and winding strand material, and by the use of which my method can be commercially practiced.

Figure 2 is a top plan view.

Figure 3 is an end elevation of a reel.

Figure 4 is a sectional elevation of a reel.

Figure 5 is a section on line 5—5 of Figure 4.

Figure 6 is a side elevation of a reel with the strand material wound thereon.

5

Figure 7 shows a stretched skein formed by the hands of the operator.

Figure 8 shows a manually manipulated bunch in a hand of the operator.

Figure 9 is a side elevation of turning mechanism for the reel carrying head.

Figure 10 is a side elevation similar to Figure 9 but showing the parts in a different relation from that seen in Figure 9.

Similar numerals indicate corresponding parts. 15

Referring to the drawings:

In order to illustrate one method of curling the strand, I have shown in Figure 1 a construction conforming to that disclosed in the Sedgley Re-issue Patent No. 18,576, in which the frame 1 of 20 the machine has an electric motor 2 mounted on it. The shaft of the motor carries a pulley 3 around which passes a belt 4 which also passes around a pulley 5 mounted on a shaft 6. The shaft 6 has fixed to it a gear 7 which meshes with a gear 8 fixed to a shaft 9 journaled in the frame. The shaft 9 carries a roll 10 which forms a driving deforming roll, and a driven deforming roll 11 is in free rolling contact with the roll 10. The roll 11 is mounted on ball bearing journals 30 12 having adjusting screws 13 to regulate the pressure during the deforming operation. These rolls have a desired contour to deform the metallic strand 14 in cross section, and if they have a smooth surface the strand will be rolled into a 35 flat ribbon form with four abrading edges.

The metallic strand 14 usually in the form of a round wire is wound on spools 15 mounted on spindles 16 and having tension devices 17 which create a hold-back tension on the spools. The 40 wire passes to the deforming rolls 10 and 11 through a guide 18, and from the rolls 10 and 11 around a guide 19 and over a curling edge 20 to the take-up rolls 21, the lower one of which has its shaft intergeared with a shaft 22 which has a 45 gear 23 meshing with a gear 24 on the shaft 6. The journals of the upper roll 21 have pressure adjusting screws 25.

The result of such construction is that the deformed metallic strand is drawn under a controlled tension over a curling edge imparting to it an inherent tendency to curl and form a coreless, helical strand. As soon as the strand leaves the take-up rolls 21, it assumes the form of a 50 55

helical, coreless strand with adjacent coils preferably close together.

The foregoing operation is that set forth in the Sedgley Reissue Patent No. 18,576, aforesaid, and my present invention relates more particularly to the formation of a flexible resilient metallic bunch from a strand of this type.

The strand is wound with its tension released and in an unstretched condition on a reel which 10 may be in the form of a spindle, mandrel, spool or core.

The winding mechanism is driven by an electric motor 26 which drives a reduction gearing 27 connected by shaft 28, having a flexible coupling 29, with the driving shaft 30 of the winding mechanism, the journals of the shaft 30 being resiliently supported and counter balanced. The shafts 28 and 30 are intergeared.

The driving shaft 30 has a driving cone 31 20 which is continually driven.

I employ a plurality of cores 32 each of which is carried by a shaft 33 journaled in a rotatable head 34 and provided with a friction member 35. The friction members 35 are progressively 25 brought into driving connection with the driving cone 31 by intermittent rotation of the head 34 so that while a core is being wound, a wound core will be accessible to the operator.

The head 34 is fixed to a shaft 35 journaled in 30 the frame 36 of the winding mechanism and such frame is preferably connected with the frame of the curling machine.

The shaft 35 has fixed to it a cam 37 having cam faces corresponding in number to the number of cores on the rotatable head 34, and, as illustrated, three cam faces are shown. The cam 37 controls the intermittent rotation of the head 34 and is controlled by a bar 38, see Figures 9 and 10, suitably guided to slide beneath the cam 37. The bar 38 has at one end a pin and slot connection 39 with a lever 40 fulcruming on the frame of the winding machine. The other end of the lever 40 is pivotally connected with a controlling rod 41 which may be automatically actuated in timed relation with the revolutions of a core being wound or controlled by the operator in any desired manner. The bar at its forward end has longitudinally adjustable on it a cam 42. The bar 38 is recessed at 43 to permit the turning 40 of the cam 37, and it is also recessed at one side to receive an angularly shaped latch 44 pivoted to the bar 38 to swing laterally on its pivot. The winding head frame has a latch block 46 fixed to it and provided with a pin or boss 47 cooperating 50 with the latch 44 to cause it to be positioned beneath the cam 37 to prevent its turning or to be moved out of the path of the cam when the rotating head 34 is to be turned to position an unwound core in winding position. This turning of the head 34 begins when the cam 42 on the bar 38 is moved beneath the cam 37 and is completed by a shoulder 48 at the end of the recess 43. When the bar moves in one direction the latch is 55 swung out of position beneath the cam 37 by the latch block pin and when moved in the reverse direction the latch is moved by the latch block pin beneath the cam 37. For a more detailed description of the construction and operation of the winding mechanism, reference is directed to the Sedgley Patent No. 2,120,944 of June 14, 1938.

The controlling rod 41 is controlled by a gear 48 driven by the driving mechanism of the curling machine so that when a predetermined length 70 of curled strand has been wound on a reel, the

rotatable head will turn to bring an unwound reel into winding position.

The controlling rod 41 is eccentrically connected with the gear 48, which latter meshes with a worm 49 on a shaft 50, which latter has 5 a worm 51 meshing with the gear 7, see Figure 1. The parts are so timed that a driven reel revolves at a comparatively slow speed.

The operator cuts the strand between a reel being wound and a wound reel and the strand 10 material which is on a wound reel is ready for the stretching and coil interlocking operation.

If such operation is to be done manually the operator removes the mass of wound strand in a loose form with his two hands and stretches it 15 into an elongated skein formation which causes coils of adjacent strands to open up and lie between coils of other strands so that when the skein is released and worked together by the hands of the operator, the coils of adjacent 20 strands will interlock substantially throughout the metallic bunch which has been formed.

If the strand material wound on the reel with the tension relaxed is to be mechanically stretched, an expansible and contractible reel can 25 be employed which after the winding operation has been completed can be automatically expanded and retained in an expanded condition a sufficient length of time to permit the operator to remove the wound material from its reel. 30 This can be accomplished in a number of different ways and in order to illustrate one manner of doing this, I have shown the reels, see Figures 3 and 4, as consisting of sections 53 and 54 connected by links 55 with a controlling rod 56 keyed 35 to a tubular shaft 57 on which a friction member 35 is mounted. The inner end of the controlling rod 56 travels in the path of a stationary cam 58, so that when the reel carrier is tripped to move a wound reel out of winding position, the 40 reel sections will be expanded, and, due to the dwell 59 of the cam, see Figure 1, will be retained in expanded condition and cause the wound material to assume the contour of an elongated skein, thus causing an interlocking of coils of 45 adjacent turns.

Springs 60 and 61 cause the retraction of the reel sections when a controlling rod passes off of the cam 58.

The mass of wound strand material is removed 50 from the reel on which it has been wound and stretched, and if desired, manually manipulated by the hands of the operator to further interlock the coils of adjacent strands and form a flexible and resilient metallic bunch with adjacent coils 55 interlocked substantially throughout the mass of the bunch.

The take up rolls 21 are preferably run at a constant speed so that the helical, coreless strand is delivered at a constant rate.

The operation will now be clear to those skilled in this art and is as follows: The metallic strand is preferably deformed, curled and wound up in a continuous operation. The strand is drawn from the tensioned spools 15, deformed by the rolls 10 65 and 11, and is drawn under tension by the take-up rolls 21 over the curling edge 20. As soon as the strand leaves the take-up rolls it assumes the form of a helical, coreless strand with adjacent coils preferably close together. The operator 70 winds the free end of the strands around a reel 32 which is in winding position, and the curled strand is wound up under a released tension without stretching the strand. A mass of curled wire is wound up in a loose condition on the reel in 75

this manner and when a sufficient amount has accumulated for the desired size of bunch to be formed, the parts are so timed that the rod 41 will move the bar 39, and latch block pin 48 rocks latch 44 out of the recess in the bar. The cam 42 slides under the cam 37 partially turning it. The shoulder 48 completes the turning operation and the latch moves beneath the cam 37 to hold it stationary during a winding operation.

As the rotatable head 34 turns, the rod 56 of a wound reel comes into the path of the cam 52, thereby moving the rod 56 inwardly to cause the links 55 to expand the reel sections 53 and 54. The reel sections are retained in expanded condition due to the dwell 59 until the rod 56 passes beyond the cam 58. The springs 60 and 61 then return the reel sections to their closed position. The operator cuts the strand or strands between a wound reel and a reel to be wound and while the reel is expanded removes the elongated skein and allows it to contract to cause the interlocking of coils and formation of the flexible and resilient metallic bunch. He may work it manually into a bunch to cause a more thorough interlocking 25 of coils of adjacent turns, or pushes it through a funnel to accomplish the same purpose.

If the cam 58 is not used, the reels will remain in their contracted position or a non-sectional reel may be used as shown in Figure 6, for the winding of the strand. In this figure, I have shown a wound reel with the strand severed and the rotatable head 34 would now be stationary. The operator removes the loose mass of wound wire by spanning the upper portion of the cylindrical mass with the thumb and fingers of one hand and the lower portion with the thumb and fingers of the other hand, and in this manner withdrawing the mass from the open end of the reel. He, now, while still holding the mass with his two hands, moves his hands apart, thus producing an elongated skein with the turns stretched to open up the spacing between the coils of the strand, and permit coils of one turn to be disposed between adjacent coils of another turn. When the skein is released, the tension inherent in the strand will cause the interlocking of the coils of adjacent turns. The operator may now take the bunch in the palm of one hand and by a rotating or compressing movement of his two hands cause a more intimate interlocking of the coils of adjacent turns as shown in Figure 8.

I preferably employ reels having a comparatively small diameter, and I have found reels which are less than two inches in diameter give very advantageous results.

It will be clear from Figures 1 and 2, that one or more strands may be processed and wound up to form a quantity sufficient for a single bunch, and Figure 1 shows clearly how the strand or strands form a loop due to the relative speed of

the winding reel and the take-up rolls and thus prevent stretching of the coils of the tensioned curled strand during the winding operation.

Having thus described my invention, what I claim as new and desire to secure by Letters Patent is:

1. The method of forming a flexible and resilient metallic bunch from a tensioned, coreless, helically curled, metallic strand, which consists in winding the strand in a tensioned released and unstretched condition around a reel, stretching the wound material after the winding operation is completed, into the form of an elongated skein to cause an interlocking of coils of adjacent turns, releasing the skein to form a bunch, and exerting 15 a pressure against the material of the bunch to cause a more thorough interlocking of coils of adjacent strands throughout the area of the bunch.

2. The method of forming a flexible and resilient metallic bunch from a tensioned, coreless, helically curled, metallic strand, which consists in winding the strand in a tension released and unstretched condition around a reel, mechanically stretching the wound material by expansion of 25 the reel after the winding operation is completed, into the form of an elongated skein to cause an interlocking of coils of adjacent turns, releasing the skein to form a bunch, and exerting a pressure against the material of the bunch to cause 30 a more thorough interlocking of coils of adjacent strands throughout the area of the bunch.

3. The method of forming a flexible and resilient metallic bunch from a tensioned, coreless, helically curled, metallic strand, which consists 35 in winding the strand in a tension released and unstretched condition to provide an elongated mass of strand material, severing the strand, manually stretching the strand material into the form of an elongated skein to cause an interlock- 40 ing of coils of adjacent turns, releasing the skein to form a bunch, and manually compressing the bunch to cause a more thorough interlocking of coils of adjacent turns throughout the area of the bunch.

4. The method of forming a flexible and resilient metallic bunch from a coreless, helically curled strand, which consists in winding the strand in an unstretched condition into the form of an elongated cylinder, stretching the cylindrical mass of wound strand after the winding operation is completed to stretch and space the coils of the turns and permit coils of one turn to move into the space between coils of adjacent turns, releasing the mass to permit the turns to 50 contract due to the tension inherent in the strand and thereby cause an interlocking of coils of adjacent turns and the formation of the bunch with an annular disposition of the turns in the bunch.

SYLVESTER W. GRATER. 60
